ATTORNEYS

UNITED STATES PATENT OFFICE.

JOHN OLAF LINDEN, OF CHICAGO, ILLINOIS.

MASSAGE DEVICE.

Application filed November 20, 1923. Serial No. 675,894.

To all whom it may concern:

Be it known that I, JOHN O. LINDEN, a citizen of the United States, and a resident of Chicago, in the county of Cook and State 5 of Illinois, have invented new and Improved Massage Devices, of which the following is a full, clear, and exact description.

This invention has relation to a means for lowering the internal temperature of a hole 10 device and has particular reference to such a means for use in connection with massaging devices whereby the temperature of the massaging surface of the device is controlled from the interior temperature of 15 the device.

As a further object the invention contemplates a means which is especially designed for lowering the internal temperature of a device of this character in order to cool the 20 massaging surface or surfaces without the use of ice which is not always available and which offers certain inconveniences in connection with its handling.

More specifically the invention contemplates a member having a hollow body into which removable containers are adapted to be inserted that contain a substance which when released into the body functions to lower the temperature thereof for cooling 30 one or more of the surfaces, together with means operable from the exterior of the body for establishing communication between said container and the interior of the body.

As a further object the invention contemplates a device of the character set forth which is comparatively simple in its construction, inexpensive to manufacture, and which is highly efficient in its purpose.

With the above recited and other objects 40 in view, the invention resides in the novel construction set forth in the following specification, particularly pointed out in the appended claims and illustrated in the accompanying drawings, it being understood that 45 the right is reserved to embodiments other than those actually illustrated herein to the full extent indicated by the general meaning of the terms in which the claims are expressed.

50 In the drawings—

Figure 1 is a plan view of the means incorporated in a massaging device.

Fig. 2 is a plan view with the cover of the device removed.

55 Fig. 3 is a detail enlarged sectional view

taken approximately on the line 3—3 of Fig. 1.

Fig. 4 is an enlarged end view of the cartridge or container member removed.

Referring to the drawings by characters 60 of reference, 10 designates the body of a hollow receptacle, the open end of which is closed by a cover 11 carrying a suitable gasket 12 for sealing the device against entrance or escape of fluids. Within the body a pair 65 of internally threaded bosses 13 are formed in which screws 14 are anchored, which extend through the cover for securing the cover in place and impinging the gasket on the edge of the body. At one end the body 70 is formed with a recess 15 which has communication with the interior by means of an opening 16, the diameter of which is less than the diameter of the recess whereby a shoulder 17 is formed. The outer end of 75 the recess is internally threaded as at 18 to receive a screw plug 19. The annular gasket 20 is positioned against the shoulder and is positioned against the shoulder and is adapted to have forced thereagainst by the screw plug 19 the annular bead 21 of the 80 closure cap 22 of a cartridge or receptacle 23, the opposite end of which cartridge is formed with a semi-spherical head. The semi-spherical head is provided with an axial opening 24 and is provided with an inwardly extending boss 25 constituting a valve seat. A valve 26 is arranged with the cartridge or receptacle 23 and is normally 85 pressed by a spring 27 into contact with the seat 25 whereby the opening 24 is sealed. The cartridge or receptacle 23 is adapted to contain a suitable substance S such for example as sulphur dioxide which when released therefrom expands in the form of a vapor for setting up a cooling action. The 90 cartridge or receptacle 23 is inserted through the opening 16 with the bead or rim 21 resting against the gasket 20. The screw plug is then employed to retain the cartridge in place and at the same time set up an impinging action of the rim or bear against the gasket for sealing the opening 16 against the entrance or exit of fluid. In order to provide means for establishing communication between the interior of the cartridge or 95 receptacle 23 and the interior of the body 10 which is operable from the exterior of the body, an opening 29 is formed in the body at a point diametrically opposite the opening 16. The screw is provided with an exten-

100
105
110

2
 nally disposed knurled head 30 and is formed at its inner end with an axially extending shank 31. A pin 32 having a peripheral longitudinal groove 33 is arranged in the 5 opening 24 of the cartridge. The free terminal of the shank 31 is normally disposed slightly out of contact with the pin 32. Preferably the shank adjacent its free terminal is guided by an opening 34 in a cross 10 bar 35, the opposite ends of which cross bar are received in grooves 36 in the bosses 13.

In use and operation after the body is sealed and the cartridge is positioned and sealed in place as illustrated in Fig. 3, the 15 operator manipulates the screw head 30 to move the shank 31 into contact with the pin 32 which is thus forced into engagement with the valve head 26 for unseating the same from the seat or boss 25 against the 20 action of the spring 27. The groove 33 in the pin 32 thus establishes communication between the interior of the cartridge and the interior of the body 10 whereby the substance S is released and expands to lower the 25 internal temperature of the body, thereby cooling the operating surface of the body. After the expanded vapor or substance S has expended its energy, and the device has performed its function, the cartridge or container 30 23 may be readily removed by unscrewing the plug 29 for reinsertion of a new cartridge. The cartridges or containers may be refilled through the valved end or by removing the closure caps 22.

35 I claim:

1. A massage device comprising a hollow receptacle having an external socket in one side thereof and an opening establishing

communication between the interior of the receptacle and the socket, a container insertable in said opening provided with an inwardly opening valved outlet at its inner end, means for normally maintaining the valved outlet in closed condition, a marginal bead on the outer end of the container, means engageable in the socket for clamping the bead in position in said socket with the major portion of the container extending into the receptacle, a longitudinally grooved pin positioned in the valved outlet with a portion thereof projecting outwardly therefrom, and a threaded element projecting through the wall of the receptacle at a point diametrically opposite the socket, said element having an exterior manipulating head for effecting axial movement of the grooved pin inwardly in the valved opening whereby to open the same to permit of the escape of the contents of the container into the interior of the receptacle. 40 45 50 55 60

2. A massage device comprising a hollow body having an open end, a gasketed cover fitted thereover, said receptacle having diametrically disposed openings in the side walls, a container partially insertable in one of the openings, means for sealing the container in place in said opening, an expansible substance in said container adapted upon release into the receptacle to change the temperature of said receptacle, an element extending through the other opening and axially movable therethrough, said element being operable from the exterior for releasing the contents of the container into the interior of the receptacle. 65 70

JOHN OLOF LINDEN.
